SAFETY DIAPHRAGM

Anthony J. Nerad, Schenectady, N. Y., assignor
to General Electric Company, a corporation of
New York

Application April 16, 1936, Serial No. 74,805

1 Claim. (Cl. 220—89)

This invention relates to safety diaphragms for use in connection with tanks or containers for containing fluid such as condensers for condensing steam or other fluid discharged from a turbine or the like. These safety diaphragms are provided as a safety means to protect such tanks or containers in case the pressure to which these tanks are exposed should assume dangerous values. The safety diaphragm is usually in the form of a thin plate of non-metallic material which breaks or bursts in case the pressure within the tank or container reaches a certain value.

The object of the present invention is to provide an improved construction and arrangement of safety diaphragms whereby breaking of the diaphragm and consequently relieving the pressure in the tank to be protected is assured at a substantially fixed pressure while using a stronger, stabler and cheaper material for the diaphragm.

For a consideration of what I believe to be novel and my invention, attention is directed to the following description and the claims appended thereto in connection with the accompanying drawing.

In the drawing, Fig. 1 illustrates a safety diaphragm arrangement embodying my invention in connection with a mercury vapor condenser; and Fig. 2 is an enlarged view of a portion of Fig. 1.

Mercury vapor condensers are used to condense mercury vapor exhausted from the last stage or stages of mercury turbines. Failure of the supply of the condensing agent, in this case water, may result in high pressures of destructive magnitude in the condenser. Often the mercury vapor is associated with other gases, for instance hydrogen, which under certain conditions may lead to explosion rendering it necessary to protect mercury vapor condensers.

Referring now more specifically to Fig. 1, the arrangement comprises a mercury vapor condenser 10 which has an open wall portion 11 secured to a chamber 12. The latter comprises an outer cylindrical wall 13 and end plates 14 and 15 welded to the outer cylindrical wall. The plate 14 is secured to the open wall portion 11 by a weld 16. The end plate 15 has an opening 17 connected to a discharge conduit 18 which may lead to a flue or other point to which it is desired to conduct mercury vapor or other gases in case of an explosion. In accordance with my invention I provide a safety diaphragm in the form of a membrane, preferably a thin steel plate 19, with its outer edge portion securely held between two sealing rings 20 and 21. The ring 20 is welded to the end plate 14 and the ring 21 is

welded to a holding ring 22. The latter is securely held and tightened together with the end plate 14 by a plurality of bolts and nuts 23. The pressure within the condenser is normally considerably below atmospheric pressure. Hence, one side of the diaphragm is subject to sub-atmospheric pressure, whereas the other side of the diaphragm in the present instance is subject to atmospheric pressure, the pressure difference tending to force the diaphragm which may have a diameter of the order of 20 inches into the open wall portion 11 of the condenser. In order to relieve the stresses thereby set up in the diaphragm, I provide a support for the central portions of the diaphragm or, from another viewpoint, for reducing movement of the diaphragm towards the condenser 10. This support is in the form of a grid 24 closely spaced with the diaphragm and securely fastened to the end plate 14 by means of a plurality of screws 25. During normal operating conditions the side of the diaphragm facing the condenser engages the grid 24. If during operation the pressure in the condenser for some reason, for instance, an explosion therein, increases to a certain extent, the diaphragm is forced outward against the atmospheric pressure until it bursts. In accordance with my invention I provide means in the form of a knife member or members to cut open the diaphragm as it is forced outward a certain extent. This knife or cutting member in the present instance is in the form of a ring 26 slightly spaced from the left-hand or outer side of the diaphragm and secured to a shoulder formed on the holding ring 22 by an annular weld 27. The cutting edge of the ring 26 adjacent the diaphragm is sharp and preferably provided with cutting teeth 28, as shown in Fig. 2. With this arrangement a considerable portion of the diaphragm is cut out by the knife 27 as soon as the diaphragm is moved outward a certain distance in response to a predetermined increase in pressure in the condenser.

Having described the method of operation of my invention, together with the apparatus which I now consider to represent the best embodiment thereof, I desire to have it understood that the apparatus shown is only illustrative and that the invention may be carried out by other means.

What I claim as new and desire to secure by Letters Patent in the United States is:

A safety diaphragm arrangement for mercury vapor condensers including the combination of a chamber having an open end plate for connection with an open wall portion of such condenser, a grid member secured to the opening in said end

plate, means including a thin metal plate on the side of the grid member facing away from the condenser to close completely said opening, a cutting element adjacent the diaphragm on the side of the diaphragm facing away from the condenser to cut open the diaphragm as the latter is forced outward in response to a predeter-

mined increase in pressure in the condenser, and a ring bolted to the end plate to support the cutting element and to force an outer edge portion of the thin metal plate into fluid-tight relation with the end plate.

ANTHONY J. NERAD.
